UNITED STATES PATENT OFFICE.

JAMES G. PORTTEUS, OF MARION, INDIANA, ASSIGNOR OF ONE-HALF TO EDWARD L. ADREON, JR., OF ST. LOUIS, MISSOURI.

RAIL-ANTICREEPER.

977,678.

Specification of Letters Patent.

Patented Dec. 6, 1910.

Application filed June 16, 1910. Serial No. 567,193.

To all whom it may concern:

Be it known that I, JAMES G. PORTTEUS, a citizen of the United States, residing at Marion, Indiana, have invented a certain new and useful Improvement in Rail-Anti-creepers, of which the following is a full, clear, and exact description, such as will enable others skilled in the art to which it appertains to make and use the same.

- 10 This invention relates to rail anti-creepers, namely, tie-plates and devices that are used in railway track structures for holding the rails in position and preventing them from creeping or moving longitudinally.
- 15 One object of my invention is to provide a tie plate or rail anchor which is so designed that it grips the base flange of the rail with a yielding pressure, thereby overcoming the necessity of using wedges or other separate
- 20 fastening devices for connecting it to the rail and also eliminating the possibility of its working loose accidentally and becoming detached from the rail as often occurs with devices of this character which depend on a
- 25 snug fit with the base flange of the rail to hold them in position.

Another object is to provide a tie plate or rail anchor that comprises rail-flange-engaging members and a connecting member that extends under the rail, said members being so constructed that they exert a yielding clamping action on the top and bottom faces of the base flange of the rail.

Another object is to provide a device of the character described that comprises a resilient portion which extends under the base flange of the rail and flange-engaging members connected to said resilient portion and designed in such a manner that they can be sprung over the base flange of the rail when said resilient portion is placed under tension, the resiliency of said portion causing the flange-engaging members thereon to clamp the base flange of the rail so tightly that it is practically impossible for the rail to creep or for the device to become accidentally detached from the rail.

Another object is to provide a device of the character described which is so designed that it will grip the rail more tightly as the weight or load on the rail is increased.

Another object is to provide a rail-supporting device or tie plate which possesses a certain degree of resiliency that makes it particularly adapted for use on concrete ties

or other supporting foundations which have no elasticity. And still another object is to provide a rail anchor or anti-creeper which is equipped with means for setting it up or arranging it in operative position on the rail.

Other objects and desirable features of my invention will be hereinafter pointed out.

While I have herein shown my invention embodied in tie plates and an anti-creeper which are so designed that the longitudinal movement or creeping of the rail causes them to engage the rail more tightly, I do not wish it to be understood that my broad idea is limited to tie plates and anti-creepers having this feature or in fact to tie plates and anti-creepers of any particular type or design as my invention, broadly stated, consists in a tie plate or rail anchor designed in such a manner that it is held on the rail or connected to the rail by a yielding clamping pressure irrespective of whether it is immovable or can turn relatively to the tie or foundation with which it coöperates.

Figure 1 of the drawings is an elevational view of a rail anchor constructed in accordance with my invention illustrating the manner of applying the device to the rail; Fig. 2 is a top plan view of the parts shown in Fig. 1; Fig. 3 is an elevational view illustrating the device arranged in operative position on the rail; Fig. 4 is a top plan view illustrating the operative position of said device; Fig. 5 is a top plan view illustrating a slightly modified form of rail anchor; Fig. 6 is an elevational view illustrating a tie plate constructed in accordance with my invention, and particularly adapted for use on concrete ties; Fig. 7 is a top plan view of the device shown in Fig. 6; Fig. 8 is an elevational view of another form of tie plate constructed in accordance with my invention; and Fig. 9 is a top plan view of the tie plate shewn in Fig. 8.

Referring to Figs. 1 to 4 of the drawings which illustrate a rail anchor or anti-creeper constructed in accordance with my invention, A designates a cross-piece or portion of the device which passes underneath the base flange 1 of the rail, and B and C designate rail-flange-engaging members on the portion A which are adapted to engage the top face of the base flange of the rail when the device is arranged in operative position, as shown in Figs. 3 and 4. The

device is preferably formed of malleable-
iron or some other suitable metal that pos-
sesses a certain degree of elasticity and the
flange-engaging members B and C are
5 formed integral with the portion A that
extends under the base flange of the rail.
The device can be formed in various ways
to obtain the desired yielding clamping ac-
tion on the rail but I prefer to camber the
10 part A slightly or curve it in such a manner
that the crown or middle part 2 thereof will
bear against the under side of the base
flange of the rail and thus cause the flange-
engaging members B and C to be forced
15 tightly against the top face of the base
flange of the rail. The flange-engaging
members B and C consist of arms which
project toward each other and they are
spaced far enough away from the cross-
20 piece A of the device to form pockets which
receive the base flange of the rail, the under
sides or faces of said members which bear
upon the flange of the rail being so shaped
that they do not bear upon the edge portions
25 of the base flange of the rail. In other
words, I prefer to form the members B and
C in such a manner that when the device is
arranged in operative position, as shown
in Fig. 3, clearances 3 will be provided for
30 both longitudinal edges of the base flange
of the rail and thus locate the clamping
pressure at points between the vertical web
1^a of the rail and the longitudinal edges
of the base flange of the rail. The under
35 sides or faces of the members B and C which
bear upon the top face of the rail flange
are preferably inclined or arranged at an
angle relatively to the portion A of the de-
vice so that they will conform approxi-
40 mately to the top face of the rail flange,
and, if desired, the member B can be pro-
vided with a lip or extension B' so as to in-
crease the bearing area of said member on
the rail flange, said extension B' being of
45 less thickness than the body portion of the
clamping member B so as to impart a cer-
tain degree of resiliency to said extension
and thus enable the device to be arranged in
operative position more easily than would
50 be possible with a perfectly rigid flange-
engaging member.

The device is so proportioned that it can
be sprung into position on the base flange
of the rail by arranging the portion A under
55 the rail and at approximately right angles
thereto, and inserting one edge of the rail
flange under the member B, as shown in
Fig. 1, and then springing the portion A
upwardly so that the other flange-engaging
60 member C will be raised high enough to lap
over or catch onto the flange of the rail
when the portion A is twisted or turned
bodily relatively to the rail, as shown in
Fig. 4.

65 The cross-piece or portion A of the device

is provided at one end with a strut 4 which
is adapted to engage a tie T and thus hold
the portion A in such a position that it can-
not slip off the base flange of the rail. This
strut 4 lies at an angle relatively to the part 70
A of the device and thus holds the flange-
engaging member C a definite distance from
the tie and a farther distance from said tie
than the member B. The clamping pressure
which the members B and C exert on the 75
base flange of the rail is so great that it will
be practically impossible for the rail to
creep but in case the rail should creep
slightly, the longitudinal movement of the
rail in the direction indicated by the arrow 80
in Fig. 4 will cause the member B to move
toward the tie and thus increase the clamp-
ing action of both the members B and C on
the flange of the rail. The strut 4 is pro-
vided with a vertical web 4^a that abuts 85
against the side face of the tie T and also a
portion 4^b that laps over the top face of the
tie, and a device 5 is adjustably mounted in
said strut so as to bear against the edge of
the base flange of the rail and thus twist or 90
turn the portion A relatively to the rail
when the device 5 is tightened. It will, of
course, be understood that this device 5 is
used merely for setting up the anchor or
moving the part A from a position at right 95
angles to the rail, as shown in Fig. 2, into
the position shown in Fig. 4, but it forms a
very convenient means for arranging the
anchor in operative position after the flange-
engaging member C has been sprung up- 100
wardly onto the flange of the rail.

In Fig. 5 I have illustrated a slightly
modified form of my invention in which the
portion 4^b of the strut that laps over the top
of the tie is omitted, said strut being pro- 105
vided with a web 4^a that bears against the
side face of the tie.

From the foregoing it will be seen that it
is practically impossible for an anchor of
the construction above described to become 110
accidentally detached from the rail or slip
off the rail for it is retained in position by
the resiliency of the cambered portion A of
the device which causes the clamping mem-
bers B and C to exert downward pressure on 115
the base flange of the rail at points between
the vertical web of the rail and the longi-
tudinal edges of the base flange, the rail be-
ing clamped securely at three points, namely,
the middle of the bottom face of the base 120
flange and on the top face of the base flange
between the vertical web and the longitudi-
nal edges of said flange. Most of the rail
anchors which have heretofore been in use
depended either upon fastening devices or 125
on a snug fit with the base flange to retain
them in operative position, but in my im-
proved construction the anchor is securely
clamped to the base flange of the rail by the
resiliency of the portion of the anchor which 130

passes under the rail. Furthermore, in my construction the members which hold the rail down bear upon the top face of the base flange at points some distance inwardly 5 from the longitudinal edges of said flange.

The members B and C are preferably provided with strengthening ribs 6 that merge into the cross-piece A of the device, and the strut 4, which is integrally connected to the 10 member C and to the portion A, is approximately T-shaped in cross section, the adjustable device 5 which is mounted in said strut either being threaded through a screw-threaded opening in a sleeve 7 formed integrally with the strut or through a separate 15 threaded member connected to the strut.

In Figs. 6 and 7, I have illustrated a tie plate constructed in accordance with my invention that is particularly adapted for use 20 on concrete ties T' or other structures which have no elasticity. Said tie plate comprises a cambered base portion A² and flange-engaging members B² and C² which are formed integrally with the base portion A², said 25 flange-engaging members being of substantially the same shape as the flange-engaging members shown in Fig. 1 so as to exert a clamping pressure on the base flange of the rail at points between the vertical web of the 30 rail and the longitudinal edges of the rail and thus securely hold the rail in position. The base portion A² is provided at one end with an extension 8 through which a fastening device 9 passes so as to pivotally connect 35 said base portion to the tie, and the opposite end of the base portion is prevented from moving upwardly by means of a fastening device 10 connected to the tie and provided with a head that laps over the edge of said 40 base portion, as shown clearly in Fig. 6, the fastening devices that are used for this purpose being of any preferred design but constructed in such a manner that the base portion of the device can twist or turn relatively 45 to the tie when the rail creeps in one direction and thus force the members B² and C² farther onto the base flange of the rail. A tie plate of this construction not only holds the rail securely down on the tie but it also 50 has the desirable feature of being forced onto the rail more tightly by any longitudinal movement or creeping of the rail; this, of course, being due to the fact that the base portion of the device is pivotally connected 55 at one end to the tie and is free at its opposite end so that it can turn or twist relatively to the rail. In addition to these desirable features, the tie plate shown in Figs. 6 and 7 possesses the still further desirable 60 feature of being resilient or having sufficient elasticity to absorb the shocks which the rail is subjected to when in service, thus making it particularly adapted for use on concrete ties and other supporting foundations which are perfectly rigid. And still

another desirable feature of such a tie plate is that the members B² and C² will be forced more snugly into engagement with the rail when the weight or load on the rail is increased, owing to the fact that the downward 70 pressure which the rail exerts on the cambered portion A² tends to straighten out said cambered portion or place it under greater tension which, of course, results in an increased clamping pressure of the members 75 B² and C² on the base flange of the rail.

The tie plate shown in Figs. 8 and 9 is of practically the same construction as the tie plate shown in Figs. 6 and 7 and possesses all the desirable features of such a construction but it is primarily intended for use on a wood tie and comprises an arm 8^a which projects downwardly from the base portion A² so that it will bear against one of the side faces of the tie and thus form a fulcrum 85 about which said base portion can turn so as to cause the flange-engaging members B³ and C³ to be forced farther onto the base flange of the rail. The base portion A³ of the plate is connected to the tie by means of 90 spikes 11 which preferably lap over the base flange of the rail, as shown in Fig. 9, and the elongated openings 12 in the base portion A³ through which said spikes 11 pass are so proportioned that the base portion A³ can 95 twist or turn slightly around the arm 8^a as a fulcrum. In setting up a tie plate of this construction I prefer to have each of the spikes 11 bear against one end of the elongated opening 12 through which it passes in 100 such a manner that the spikes impart a twisting or turning movement to the base portion A³ when they are being driven into the tie so as to securely lock the base portion A³ in its adjusted position and prevent it 105 from moving into such a position that the flange-engaging members B³ and C³ can slip off the base flange of the rail, this feature being illustrated in Fig. 9.

Having thus described my invention, what 110 I claim as new and desire to secure by Letters Patent is:

1. A device of the character described, comprising flange-engaging members which bear upon the top face of the base flange of the rail at points between the edges of said flange and the web of the rail, and means for causing said members to exert a downward clamping pressure on the rail, said members being so formed that they do not 115 bear upon the top face of said base flange adjacent the longitudinal edges of said flange.

2. A device of the character described, comprising clamping members having flange-engaging faces which are so designed that 120 they do not bear upon the edge portions of the top face of the base flange of the rail, and resilient means arranged in engagement with the base flange of the rail and operating to cause said members to normally exert 125

130

a downward clamping pressure on the flange of the rail.

3. A device of the character described, comprising a cast metal portion that projects under the base flange of the rail, said portion being so formed that it is normally in tension when the device is arranged in operative position, and cast members formed integral with said portion for engaging the base flange of the rail.

4. A device of the character described, comprising a cast portion that projects under the base flange of the rail, said portion being so formed that it is normally in tension when the device is arranged in operative position, and hook-shaped flange-engaging members integrally connected to said portion and having clamping faces which are so designed that they do not bear upon the edge portions of the top face of the flange of the rail.

5. A device of the character described, comprising a cambered portion that is adapted to be arranged under the base flange of the rail with its crown in engagement with the bottom face of said flange, and flange-engaging members on said cambered portion that lap over the base flange of the rail, said members being so formed that they do not engage the longitudinal edges of the base flange of the rail or the portions of the top face of said flange which are adjacent the longitudinal edges of same.

6. A device of the character described, comprising a cast metal cambered portion whose crown bears against the under side of the base flange of the rail, and integral hook-shaped flange-engaging members on said cambered portion which are adapted to be sprung up over the base flange of the rail so as to place said cambered portion under tension and thus cause said members to exert a downward clamping pressure on the base flange of the rail.

45 7. A device of the character described, comprising two substantially hook-shaped flange-engaging members, and a cambered portion that connects said members together, said members and cambered portion being formed of cast metal and so designed that one of said flange-engaging members can be sprung up over the edge of the base flange of the rail by placing said cambered portion under tension.

55 8. A device of the character described, comprising a cambered portion that passes under the base flange of the rail and which is adapted to be placed under tension during the operation of arranging the device in position, and a pair of approximately hook-shaped flange-engaging members on said cambered portion that lap over the top face of the base flange of the rail, one of said members being provided with a reduced extension which projects beyond the inner

end of said member toward the web of the rail.

9. A device of the character described, comprising a cast metal resilient portion arranged under the base flange of the rail, integral flange-engaging members on said portion which are held pressed against the top face of said base flange by the resiliency of said portion, and means whereby the longitudinal movement or creeping of the rail in one direction causes said resilient portion to move into such a position that the clamping pressure of said flange-engaging members on the rail is increased.

10. A device of the character described constructed of cast metal and comprising a cambered portion whose crown bears against the under side of the base flange of the rail, approximately hook-shaped flange-engaging members on said cambered portion which are adapted to be sprung up over the base flange of the rail so as to place said cambered portion under tension and thus cause said members to exert a downward clamping pressure on the base flange of the rail, and means whereby the longitudinal movement or creeping of the rail in one direction causes said flange-engaging members to be forced more tightly against said base flange.

11. A rail anchor, comprising a cast metal cambered portion which is under tension when arranged in operative position, a pair of approximately hook-shaped flange-engaging members on said cambered portion which exert a downward clamping pressure on the top face of the base flange of the rail, and a strut at one end of said cambered portion that bears against a track tie.

12. A rail anchor formed of cast metal and comprising a cambered portion which is under tension when arranged in operative position, a pair of integral flange-engaging members on said cambered portion which exert a downward clamping pressure on the top face of the base flange of the rail, a strut integrally connected to one end of said cambered portion and bearing against a track tie, and an integral wing on said strut that laps over the top face of said track tie.

13. A rail anchor, comprising a cambered portion which is under tension when arranged in operative position, flange-engaging members on said cambered portion which exert a downward clamping pressure on the top face of the base flange of the rail, a strut at one end of said cambered portion that bears against a track tie, and an adjustable device carried by said strut and adapted to be forced into engagement with the rail so as to twist or turn said cambered portion relatively to the rail.

14. A rail anchor, comprising a resilient portion arranged under the base flange of the rail and provided with flange-engaging members that exert a downward clamping

pressure on the base flange of the rail, a strut projecting laterally from one end of said resilient portion and adapted to bear against a track tie, and means carried by 5 said strut for effecting a movement of said resilient portion relatively to the rail so as to force said flange-engaging members farther onto the base flange of the rail.

15. A rail anchor, comprising a cambered cross-piece provided at its ends with approximately hook-shaped flange-engaging members, one of which is adapted to receive the portion of the base flange of the rail which lies on one side of the web of the rail 10 and the other being adapted to be sprung up over the portion of the base flange on the other side of said web when the cambered portion of the device is twisted or turned relatively to the rail and placed in tension, 15 and a strut on one end of said cambered cross-piece which is adapted to coöperate with a track tie for holding said cambered cross-piece in an angular position with relation to said tie.

20. 16. A rail anchor, comprising a cambered cross-piece provided at its ends with ap-

proximately hook-shaped flange-engaging members, one of which is adapted to receive the portion of the base flange of the rail which lies on one side of the web of the rail 30 and the other being adapted to be sprung up over the portion of the base flange on the other side of said web when the cambered portion of the device is twisted or turned relatively to the rail and placed in tension, 35 a strut on one end of said cambered cross-piece which is adapted to coöperate with a track tie for holding said cambered cross-piece in an angular position with relation to said tie, and a reduced extension on the 40 flange-engaging member which first engages the base flange of the rail during the operation of arranging the device in operative position.

In testimony whereof I hereunto affix my 45 signature in the presence of two witnesses, this 11th day of June 1910.

JAMES G. PORTTEUS.
